UNITED STATES PATENT OFFICE.

CHARLES P. HIDDEN, OF PROVIDENCE, RHODE ISLAND, ASSIGNOR TO NITROGEN PRODUCTS COMPANY, OF PROVIDENCE, RHODE ISLAND, A CORPORATION OF RHODE ISLAND.

METHOD OF HYDROLYZING CYANID TO AMMONIA.

1,312,116.

Specification of Letters Patent.

Patented Aug. 5, 1919.

No Drawing.

Application filed October 3, 1918. Serial No 256,729.

To all whom it may concern:

Be it known that I, CHARLES P. HIDDEN, a citizen of the United States, residing at Providence, in the county of Providence and State of Rhode Island, have invented certain new and useful Improvements in Methods of Hydrolyzing Cyanid to Ammonia, of which the following is a specification.

This invention relates to the production of ammonia from sodium cyanid or the like, and more especially concerns an improvement upon the process disclosed in the patent to John E. Bucher, No. 1,091,425, dated Mar. 24, 1914.

15 In said patent there is described a method of fixing free nitrogen in the form of alkali metal cyanid, by forming an intimate mixture of, for example, sodium carbonate, finely divided iron and carbonaceous material, and subjecting said mixture to the action of free nitrogen, in a retort heated to a bright red heat, but preferably not above the eutectic point of the carburized iron formed.

25 In practice, the resulting mixture contains the catalytic pulverized iron, which is substantially unchanged, save that it is normally highly carburized; the alkali metal cyanid, formed by the reaction; residual coke or the like; and the residual or unconverted alkali metal carbonate,—together, frequently, with traces of compounds resulting from impurities in the coke, or other source of carbon, used.

30 The patent in question describes this production of alkali metal cyanid in detail, and thereafter sets forth the formation of ammonia through the reaction of steam upon the cyanized material, according to the equation:

It has been found in practice, however, that certain difficulties are encountered in 45 hydrolyzing the cyanid to ammonia; especially if a substantially quantitative production, or even a desirably high yield of this material, is to be afforded.

The ammonia forming reaction is an ex- 50 othermic one and if the temperature of the reactive mass rises unduly as a result of this generation of heat therewithin, it becomes impossible to obtain anywhere near a quantitative conversion of the cyanid to am-

monia; since while the reaction may be empirically expressed as per the above equation, as a matter of fact, it is very much more complex; ammonium carbonate, sodium cyanate, iron oxid, sodium ferrocyanid, etc., being formed together with the ammonia.

Some of these by-products, such as the iron oxid, are final, while others are more or less intermediate, and their extent of production depends upon the composition of the reactive mass, the temperature or temperatures at which hydrolysis is effected, the quantity of steam supplied, its condition (dry or wet), its temperature, etc.

The mass containing the alkali metal cyanid to be hydrolyzed is preferably briqueted, and may conveniently be supplied after proper cooling, direct from the cyanizing operation described in the patent to said John E. Bucher, No. 1,120,682, dated Dec. 15, 1914. In this case the cyanized briquets comprise the finely divided catalytic iron (or its equivalent), unconverted alkali metal carbonate, alkali metal cyanid, carbon, at times some sodium cyanate, possibly even some traces of sodium ferrocyanid, and traces of compounds resulting from the silicious or aluminous impurities commonly present in coke or like carbon supplying material which is not ash-free, but which is available for use in the cyanizing operation when really ash-free carbon cannot readily be obtained.

Any alkali metal cyanate initially present in the briquets to be hydrolyzed, or which is formed during the hydrolyzing operation, normally is converted to ammonia during the course of such operation if proper reaction conditions are maintained.

Similarly, the alkali metal ferrocyanid formed during the hydrolysis, or otherwise, may be decomposed, especially at the higher reaction temperatures permitted, and the cyanid formed is then converted to ammonia.

The production of ferrocyanid is, however, desirably to be avoided as far as practicable in order to obviate the necessity for maintaining such relatively high temperature for any extended period of time; since, in general, the most nearly quantitative yields appear to result from the effecting of the greater part of the hydrolyzing opera-

tion at temperatures nearer the lower limit of the range of permissible temperatures, than the upper limit of the same.

Thus I prefer to start the steaming treatment with the cyanized mass at a temperature of about 275° C. and to then allow the temperature to rise, as it of course tends to do, very gradually toward, say, from 600° C. to 650° C. I also prefer not to materially exceed the latter temperature.

The steam supplied to the cyanized briquet charge, is most desirably dry. Even then, there is still a tendency for the yield of ammonia to be far from quantitative, if the steam be supplied at or above atmospheric pressure; especially as the temperature of the mass being hydrolyzed begins to rise.

What apparently takes place in such case, is that too rapid hydrolysis is effected in the interior of a mass which is a poor conductor of heat, so that the temperature rises in parts of the charge to such an extent that the large amount of water vapor or steam present is enabled to form considerable alkali metal ferrocyanid and other undesirable products.

To thereafter efficiently decompose this large amount of ferrocyanid, requires time and the effecting of this decomposition at undesirably high temperatures which deleteriously affect the production of ammonia as such, producing rather a mixture of ammonia and undesired gaseous by-products.

I have discovered, however, that this objectionable action may be, in very large measure, overcome by treating the cyanid bearing material to be hydrolyzed, with not only dry steam but, further, by effecting the hydrolysis under reduced pressure.

In other words, a partial vacuum is created in the chamber or receptacle in which the hydrolysis is effected and the dry steam is only admitted to said receptacle at a rate such as will permit of the maintenance of said partial vacuum.

The effect of this rarefaction of the steam becomes apparent substantially as soon as any material reduction in pressure is established during the hydrolyzing operation; but I prefer to maintain the pressure in said receptacle at from but one quarter to one half of that of the atmosphere. By thus employing dry steam under reduced pressure and by suitable temperature regulation to maintain the temperature substantially throughout the reactive mass well below 600° for the major portion of the operation, very nearly quantitative yields (e.

g. 98 or 99% or more) of ammonia, in vaporous form may be obtained.

The so produced ammonia may, of course, be collected in water or in any other manner desired.

Finally, I desire to call attention to the advantage of using for the hydrolyzing operation, a charge which is briquetted rather than loosely pulverulent in character. The briquets of the type in question are exceedingly porous and particularly well adapted for hydrolysis; since no binding materials such as tar or the like, or even the heat treated residues of such material, are present in the pores of said briquets, to obstruct the free access of the rarefied water vapor to the cyanid content of said briquets.

Being thus porous, also, the briquets do not tend to locally overheat, as much as does a pulverulent mass, since the vapors can circulate more freely and thereby tend to distribute the heat evolved more equally.

Having thus described my invention, what I claim is:

1. The method of forming ammonia which comprises treating a briquetted charge of intimately mixed alkali metal cyanid, iron, carbon and an alkali metal oxygen compound, with dry steam, under a pressure below that of the atmosphere, to hydrolyze said cyanid to form ammonia and an additional amount of said alkali metal oxygen compound.

2. The method of forming ammonia which comprises treating a porous briquetted cyanized charge with dry steam, under a pressure substantially below that of the atmosphere, to hydrolyze to ammonia the cyanogen compound present in said charge.

3. The method of forming ammonia which comprises hydrolyzing a cyanized charge with dry steam, under a pressure substantially below that of the atmosphere, while maintaining the temperature of the hydrolyzing operation below 650° C. during substantially the whole of said operation.

4. The method of forming ammonia which comprises hydrolyzing a cyanogen compound with dry steam, under a pressure below that of the atmosphere, while maintaining the temperature of the hydrolyzing operation between 275° C. and 650° C. during substantially the whole of said operation.

In testimony whereof I have affixed my signature, in the presence of two witnesses.

CHARLES P. HIDDEN.

Witnesses:

ROGER N. LOBDELL,
H. F. HYLAND.
